UNITED STATES PATENT OFFICE.

DAVID C. HALE, JR., OF CINCINNATI, OHIO, ASSIGNOR TO HALE GARMENT MACHINERY COMPANY, OF CINCINNATI, OHIO.

PROCESS OF PRESSING GARMENTS.

1,148,675.

Specification of Letters Patent. Patented Aug. 3, 1915.

Application filed November 13, 1913. Serial No. 300,859.

To all whom it may concern:

Be it known that I, DAVID C. HALE, Jr., a citizen of the United States, residing at Cincinnati, in the county of Hamilton and State of Ohio, have invented certain new and useful Improvements in Processes of Pressing Garments; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to a new process of pressing garments.

The object of the invention is to utilize the necessary element of steam-moisture in the process of pressing the garment in such a manner that excessive moisture cannot take place in the garment but only sufficient moisture for the purpose of the pressing operation. The garment, when the operation of pressing is completed, is free from moisture or is dry.

The present process contemplates subjecting the garment to what may be termed flash steam, that is, the necessary quantity of water is admitted to the heated head to generate steam therein in sufficient quantities to impart to the garment the necessary moisture only for the pressing operation. In other words, the steam is intermittently generated or flashed in the head and comes in contact with the garment while the latter is being subjected to the heat of the head in pressing said head in contact with the garment. This pressing heat is sufficient to remove all dampness from the garment before the latter is taken from the machine.

The accompanying drawing illustrates a garment pressing machine through which my process may be carried out. It will be understood, however, that the machine may vary more or less and yet be suitable for carrying out the process to be described.

Referring first to the structural features of the machine, 1 designates the base from which extends a standard 2 terminating at its upper end in an overhanging arm 3 upon which the presser-head 4 is supported. The presser head incloses heating units 11 which are supplied with electric current through wires 12. Water is intermittently dis-

charged into said presser head through the pipe 13, and the said presser head is enclosed by a perforated pressure plate 14.

5 designates the buck upon which the garment is placed to be pressed by the head 4. 60 The buck is mounted upon a table 6 which is movable horizontally to bring said buck 5 to an outward position to receive the garment and is thence movable inwardly to bring said buck below the presser-head 4 65 and in a position to be elevated against the presser-head by applying foot pressure to the lever 7 which is suitably connected to the vertically movable platform 7' carrying the table. Supported upon the arm 3 is a 70 water cylinder or tank 8 that supplies a pump 9 with the necessary water to be discharged to the interior of the presser-head 4 through the pipe 13. The said pump is operated to discharge the water as required 75 to the head by means of a handle 10. The head as before stated is supplied with the necessary heating unit which may be electrical or any other source of heat generation.

The process consists in discharging water 80 to a heated presser-head to instantly generate steam therein during the operations of pressing the garment. In carrying out the process the buck is conveniently moved outward by the operator and the garment is 85 properly placed thereon. The presser-head has a sufficient temperature to quickly generate steam on the interior thereof. The water is discharged from the pump into the presser-head in this condition, the said 90 water being discharged intermittently through the operation of the pump. The buck having been moved to its co-operative position with the presser-head is elevated. At this instant the water is admitted to the 95 presser-head and the flash of steam occurs as the contact is made between the presser-head and the garment. The heat applied to the garment is of a comparatively dry character. The quantity of the steam not being sufficient to produce excessive moisture, the heat of the presser-head dries out the garment after the flashed steam is applied and serves the purpose of making the garment 100 sufficiently limp to receive the impression of the presser-head.

The presser head being heated to a suitably high temperature, the water discharged therein from the pump is quickly generated 105 into steam of a lower temperature than the 110

heat of the presser head. In the process, it will be understood that the water is discharged to the head intermittently as it may be required and is not allowed to flow into the head freely to create an excessive amount of steam.

Having described my invention, I claim.

1. A process of pressing garments, consisting in applying flashes of steam generated in a presser head to said garment, and simultaneous therewith utilizing the heat of said presser head and applying pressure to said garment, substantially as specified.

2. A process of pressing garments, consisting in applying moisture to the garment

in the form of flashed steam generated in a presser head, and further in applying heat to said garment and pressure thereto, the moisture applied through the flashed steam being of a lower temperature than the heat 20 whereby the heat relieves the garment of the moisture applied thereto in the process of pressing said garment.

In testimony whereof I affix my signature, in presence of two witnesses.

DAVID C. HALE, JR.
